UNITED STATES PATENT OFFICE

IRVING F. KENT, OF COPPER CLIFF, ONTARIO, CANADA

CHAIR FOR MINE SKIPS

Application filed October 4, 1928. Serial No. 310,338.

The present invention relates to improvements in mining apparatus and has particular reference to a chair or support apparatus adapted to support a skip during loading operation, to prevent sagging and consequent spillage.

An important object of the invention is the provision of an apparatus for effectively supporting a mine skip during the loading operation to relieve the hoisting cable of undue strain.

A further object of the invention is the provision of a skip supporting apparatus which may be automatically operated simultaneously with the operation of the delivery chute door or operated independently thereof.

Another object of the invention is the provision of a skip supporting mechanism which may be operated to an extended skip engaging position or to a retracted skip clearing position.

Still another object of the invention is the provision of apparatus of the above character which will be comparatively simple and durable of construction and reliable in operation.

Other objects and advantages of the invention will become apparent as the description progresses.

30 In the accompanying drawings forming a part of this specification and in which like reference characters are employed to designate corresponding parts throughout the same:

35 Figure 1 is a vertical fragmentary sectional view through a mine chair illustrating the chair apparatus in retracted position,

Figure 2 is a similar view showing the chair apparatus in extended skip engaging position,

40 Figure 3 is an enlarged vertical section through the skip supporting mechanism showing the apparatus disengaged from the skip,

45 Figure 4 is a similar view showing the chair apparatus extended,

Figure 5 is a perspective view of a link member,

50 Figure 6 is a perspective view of a skip engaging dog, and

Figure 7 is a transverse section taken on the line 7—7 of Figure 3.

Referring to the drawings, wherein for the purpose of illustration is shown a preferred embodiment of the invention, the numeral 55 10 generally designates a vertically extending mine shaft in which is mounted, for vertical sliding movement, a hoisting bucket or skip 11 vertically operated through the medium of a cable 12. The invention may likewise be applied to an inclined mine shaft.

At one side of the shaft 10 is formed a recess 13 forming a chamber for a pressure member including arms 14 pivoted to the side wall of the shaft at their upper ends and carrying rollers 15 journaled on a shaft 15' at their lower ends. The rollers 15 are adjusted transversely of the shaft to extended or retracted positions by means of transverse control rods 16 embodying pairs of sections connected by turn buckles 17. The rollers 15 are brought to a fixed extended position while the chair is being used, and to a fixed retracted position while the skip is hoisting from a lower level, and the chair is not in use.

At the opposed side of the shaft is provided an inclined delivery chute 18 having the outer delivery end formed flush with the side wall of the shaft. The discharge of material through the chute is controlled by a swinging gate 19 operated by conventional operating gear controlled by a rotary hand wheel 20. As noted in the drawings, the chute 18 is disposed in an underground level, designated at 21, below which is formed a chamber 22 in which is positioned a skip supporting mechanism or chair.

Supported vertically in the lower portion of the chamber 22, and flush with the side of the shaft 10, is a vertically elongated hollow 90 casing 23 having the lower portion of the outer wall in open communication with the shaft. This casing is preferably positioned on a yieldable cushion member 24, formed of rubber or other suitable material, adapted to absorb the shock imparted to the casing. The opposed side walls of the casing 23 are formed with a pair of transversely opposed upper slots 25, arranged at a downward inclination 95 toward the forward wall, and a pair of lower 100

vertically arranged slots 26 adapted to form bearings for a pair of skip engaging dogs 27.

The dogs 27, as shown to advantage in Figure 6, embody transversely elongated metallic members tapered in cross section and diminishing toward the upper edge. At the lower forward edge of the dog is formed an outwardly projecting tapered lip 28 extending the entire length of the dog. The rear side 10 of the dog is recessed to form an indented pocket 29 intermediate the ends, while the side portions are formed with bearing apertures 30. Projecting longitudinally from the upper edge portion of the dog, at each end, 15 are pivot pins 31 designed to rotatably and slidably engage the respective slots 25 and 26 of the casing 23.

The dogs are selectively adjusted by suitable operating mechanism essentially embodying an operating rod 32 disposed for vertical reciprocating movement through an opening in the top of the casing. Attached to the rod 32 and depending vertically therefrom is an enlarged operating rod section 33 formed with a pair of spaced longitudinally directed slots 34. Attached to the lower end 20 of the section 33 and depending vertically therefrom is a guide rod section 35 projecting through a suitable opening in the bottom 25 of the casing to retain the section 33 in rectilinear position. Projecting rearwardly from the intermediate portion of the section 33 is an eye 36, the purpose of which will be later described.

The operating rods just described are adapted to manipulate a pair of dog adjusting links 37 embodying relatively flat metallic members formed with solid projections 38, at the forward end, and a bifurcated extension 39 at the inner or rear end. The forward solid end 38 is formed with a longitudinal shaft receiving bore 40, while the extremities of the bifurcated extensions are formed with recesses 41. As shown to advantage in Figures 3 and 5, the inner transverse portion of the bifurcated extension 39 is formed with a V-shaped rib 42 designed to clear the operating rod in suspended position of the link. The link is connected to a dog 27 by means of 45 a transversely directed shaft 43 extending through the bearing recesses 30 of the dog and through the bore 40 of the link. The inner end of each link is connected to a slot 34 of the rod section 33 by means of a bearing pin 50 44.

As indicated in Figure 2, the dogs are mounted to releasably engage a seat bracket 45 mounted on the lower inner edge of the skip 11. This bracket is slotted at its inner edge to form a pair of vertically aligned shoulders 46 and 47 designed to engage at predetermined periods the lips 28 of the dogs.

Enclosing annularly the upper extremity of the rod 32, and extending vertically upward therefrom, is a hollow ended operating

extension rod 48, the lower portion being mounted for reciprocating movement through a vertical cylinder 49 fixed on the casing 23, while the upper portion extends through a bearing 50 mounted in the floor of the level 70 21. On the upper extremity of the extension 48 is secured an operating handle 51. About the lower portion of the extension 48, and operatively movable in the cylinder 49, is an annular piston 52 operable by compressed air or other fluid means, supplied to the cylinder through conduits 53 and 54.

As illustrated in Figure 1, the operating extension 48 may be connected with the gate operating gear by means of an operating member 55 to operate the chair mechanism 80 simultaneously with the selective opening operation of the gate.

The weight of the lugs 27, links 37, and operating rod sections are counterbalanced in excess of their weight by means of a weight 56 suspended from a cable 57 which is trained over a pulley 58. The pulley 58 is journaled in brackets formed integral with and extending from the rear wall of the casing and 90 registering with a slot therein. The opposed end of the cable 57 is attached to the eye 36 formed on the slotted rod section 33.

In operation, when the conveyor or skip 11 is initially lowered to a loading position below the chute opening, the chair operating rod is slidably actuated to a lowered position simultaneously with the opening of the chute gate 19. As previously indicated, the lowering of the operating rod may be manually effected independently of the gate by means of the handle 51 or by fluid pressure. The downward movement of the operating extension rod 48 will cause similar movement of the slotted main section 33, whereupon the inner ends of the links 37 will be lowered by gravity so as to laterally extend the lower free ends of the dogs through the openings in the forward wall of the casing 23 to project the lips into the shaft. When the material is discharged into the skip 11, the skip settles downwardly in the shaft due to the extension of the hoisting cable 12. As the skip settles under the load of the material, the shoulders of the seat bracket 45 engage the upper or lower dog lip 28 and the skip is thus rigidly held in suitable position. During the filling operation, the transverse roller operating rod 16 remains adjusted so that the roller 15 is closely adjacent to the side of the skip to prevent the top of same from tipping transversely across the shaft. The dogs will be rigidly held in skip engaging position inasmuch as the links will be arranged transversely in the casing to obviate retracted movement of the dogs. When the skip filling operation is completed, the operating rod 48 is raised when the chute door closes so that the weight 56 is free to lift the inner pivoted ends of the links 37 whenever the 110

115 120 125 130

As indicated in Figure 2, the dogs are mounted to releasably engage a seat bracket 45 mounted on the lower inner edge of the skip 11. This bracket is slotted at its inner edge to form a pair of vertically aligned shoulders 46 and 47 designed to engage at predetermined periods the lips 28 of the dogs. Enclosing annularly the upper extremity of the rod 32, and extending vertically upward therefrom, is a hollow ended operating

skip is hoisted free from the dogs 27, thus swinging the lower ends of the dogs inwardly to a retracted position within the casing as soon as the skip starts upward. The retracted position of the dogs may also be effected simultaneously with the closing of the chute door, if desired, by suitably connecting the rod 32 rigidly to the rod 48.

As indicated in Figure 4, the dogs may be extended to a skip engaging position within the shaft and the skip raised from a position below the dogs. As shown in this figure, the dogs will be raised by the contact of the skip with the under side of the protruding lips, the pivot pins 31 of the dogs travelling upwardly in the slots 25 and 26 of the casing. As soon as the bracket 45 registers with the dogs, the dogs will be released and will drop by force of gravity to a seat engaging position. Thus, it will be obvious that the mechanism is constructed to provide an effective chair or skip supporting structure designed to operate with the utmost efficiency under all conditions.

It is to be understood that the form of my invention herein shown and described is to be taken as a preferred example of the same, and that various changes as to the shape, size, and arrangement of parts may be resorted to without departing from the spirit of the invention or the scope of the subjoined claims.

Having thus described my invention, I claim:—

1. The combination with a mine shaft, a material carrying skip operatively movable therein, a material delivery chute mounted at one side of the shaft, a gate adapted to control the discharge of material from the chute, of mechanism operable to an extended skip supporting position or a retracted releasing position, and means for operating said mechanism connected with the discharge gate for simultaneous operation thereof.

2. In a chair for mine skips, a plurality of dogs mounted for swinging and sliding movement, skip engaging lips projecting from the lower ends of the dogs, a vertically movable operating rod, and links having their outer ends pivotally connected to the lower ends of the dogs and their inner ends pivotally and slidably connected to an intermediate portion of the operating rod adapted to swing the dogs to an extended skip supporting position or to a retracted releasing position upon selective movement of the operating rod.

3. The combination with a mine shaft, a hoist skip and a cable for the said hoist skip, of a pair of parallel arms mounted in the shaft and disposed to swing transversely therein, mechanism urging the said arms to an extended position in the shaft for engagement with the side of the hoist skip, and manually adjustable chairs mounted in the opposed side of the shaft disposed to engage the

lower end of the skip at the side opposed to the engagement of the arms and adjustable to extended skip supporting positions or retracted skip releasing positions.

4. The combination with a mine shaft, and a hoist skip disposed for operative movement in the shaft, of a pair of arms mounted for swinging movement in one side of the shaft, rollers journaled in the free ends of the arms, mechanism disposed to urge the roller carrying ends of the arms to extended positions in the shaft for engagement with the adjacent side portions of the skip in loading position, and a chair mounted in the opposed side of the shaft engageable with the lower end of the skip at the side opposed to the engagement of the rollers.

5. In mechanism of the character described, the combination with a mine shaft and a hoist skip reversibly movable therein, of a plurality of skip engaging dogs pivotally and slidably supported at various levels at one side of the shaft, a reciprocatory operating rod extending at one side of the shaft and adjacent the said dogs, and a plurality of links pivotally connecting the dogs with the operating rod arranged so that the operation of the rod will cause simultaneous operation of the dogs at various levels to extended skip engaging positions or retracted skip releasing positions.

6. In mechanism of the character described, the combination with a mine shaft and a hoist skip reversibly movable therein, of a dog casing mounted at one side of the shaft, an angular dog mounted in the casing having a supporting pivot extending transversely from the upper end portion, the said pivot being mounted to slide in a guide slot in the casing, a reciprocatory operating rod extending through the casing, and a link pivotally connected with the rod and with the lower portion of the dog respectively whereby the lower portion of the dog may be actuated to an extended skip engaging position or to a retracted skip releasing position.

In witness whereof I have hereunto set my hand.

IRVING F. KENT.
